UNITED STATES PATENT OFFICE

ERNST ROTH, OF LAUTAWERK, GERMANY

DISINTEGRATING MACHINE

Application filed January 4, 1926, Serial No. 79,159½, and in Germany February 16, 1925.

My invention relates to improvements in disintegrating machines.

This application is a continuation as to certain features thereof of my prior application, Serial No. 62,132, filed October 12, 1925.

In my prior application referred to I describe the type of the machine having a bi-conical hollow casing composed of two conical shells disposed with their bases or flaring ends opposite each other and provided on their inner surfaces with a number of radial ribs for the purpose set forth in my said prior application. The two conical shells revolve in opposed directions and the coarse material supplied thereto is reduced to a powder owing only to the mutual rubbing or grinding action of the material.

According to the present invention I provide in addition to the said radial ribs annular ribs on the inner conical surfaces of the two shells as will be seen in the accompanying drawing forming a part of this specification and illustrating, for purpose of exemplification, a preferred form and manner in which the invention may be embodied and practised.

In the drawing A denotes the inner conical surface of the one shell shown, R are the radial ribs and r are the annular ribs arranged in concentric relationship. Only one shell is shown in the drawings for the other one required to form a pair is of the very same construction and arrangement so that it seems unnecessary to illustrate the same.

The ribs r are not so high as the ribs R or, in other words, the top faces thereof lie in a plane considerably below the top plane of the ribs R. The purpose of the ribs r is to act in the manner of obstacles or resistances adapted to retain the particles and to prevent the same from moving too quickly in radial direction from the centre towards the periphery of the casing.

By thus retarding the movement of the material to be comminuted in radial direction the rubbing and grinding action of the particles will be prolonged and a finer powder will be obtained.

I do not of course desire to be limited to the exact construction and arrangement

shown and aim in the appended claims to embrace all modifications falling fairly within the scope of my invention.

What I claim is:—

1. In a disintegrating machine of the type set forth comprising a casing consisting of two spaced conical shells revolving in opposite directions each of said shells being provided with radial and annular ribs on their inner faces, said radial ribs extending substantially to the center of each shell. 55

2. In a disintegrating machine of the type set forth comprising a casing consisting of two spaced conical shells revolving in opposite directions each of said shells being provided with radial and annular ribs on their inner faces, the said annular ribs being of less height than the said radial ribs, said radial ribs extending substantially to the center of each shell substantially as and for the purpose set forth. 65

In testimony whereof I affix my signature.
ERNST ROTH.
